VENTILATOR

James M. Guthrie, Allison Park, Pa., assignor to
Frank R. Kelley, Pittsburgh, Pa.

Application October 13, 1942, Serial No. 461,851

2 Claims. (Cl. 98—70)

This invention relates to ventilators, and consists in a ventilator cowl of improved and simplified construction.

The object of the invention is to provide a cowl in which ventilating efficiency and economy in manufacture are obtained in most effective combination.

Experience in the art of natural ventilation has shown that greatest efficiency, particularly efficiency at low wind velocities, is obtained with a cowl of the ejector tube type, illustrated and described in Letters Patent No. 1,639,187, granted August 16, 1927 on the application of Frank R. Kelley. The body of the cowl is formed of sheet metal, and in structure may be likened to a large stovepipe elbow having a ninety degree bend. The openings at the two ends of the elbow-shaped body provide respectively the inlet and the outlet of the cowl, and the cowl body carries on the periphery of its outlet end an outwardly flared flange. In the back wall of the cowl body an ejector tube is mounted, such tube extending inward partway across the throat of the cowl and being directed towards the center of the said cowl outlet.

In service the cowl is mounted in the open atmosphere above the building or other structure to be ventilated, with the inlet of the cowl in communication with a ventilating duct extending upwardly from the building. The cowl is supported for rotation on a vertical axis, whereby the outlet of the cowl may be faced in downwind direction, with the mouth of the ejector tube faced into the wind. The moving air or wind of the atmosphere impinges upon the cowl, and some of the air streams through the ejector tube, to effect in known way and in conjunction with the buoyancy or stack effect of the air within the building the aspiration of air from the ventilating duct.

Considering the structure in greater detail, the body of the cowl is formed of a plurality of sections of sheet metal. The sections consist in short cylinders whose ends are inclined, the cylinders being (as viewed from the side) wedge-shape in outline. The so-shaped cylindrical sections are united edge to edge in the form of an elbow of substantially ninety degrees (90°) in angular extent. Manifestly, a tubular structure of this sort is an expensive thing to construct, this apart from any consideration of the cost of the flange that is subsequently provided at the outlet of the cowl, or the cost of installing the ejector tube in the rear wall of the cowl.

With these circumstances in mind, it is to be understood that the present invention consists in a cowl of the ejector tube type which is so simplified in construction that maximum economy in production is gained, this without serious loss of ventilating efficiency at wind velocities

below six miles per hour; it being understood that at wind velocities of higher value there is no difficulty in obtaining adequate ventilating effect with any of the less specialized cowls.

5 In the accompanying drawing Figure I is a view of a ventilator installation that affords an exemplary embodiment of the invention; the ventilator cowl is shown partly in side elevation and partly in vertical section, with the vane of the cowl and the ventilating uptake with which the cowl is associated shown fragmentarily. In this view certain features of design are represented in broken lines, referred to in the ensuing description of the cowl structure.

10 Figure II is a view in side elevation and to smaller scale of the ventilator, illustrating certain permissible modifications in the cowl structure.

15 In accordance with the invention, the tubular body 2 of the cowl is made in the form of a truncated cone, by virtue of which it becomes possible to construct the cowl body of a single piece of sheet metal, cut to appropriate pattern, bent into a conical tube, and the meeting edges united in a single seam.

20 The inlet of the cowl consists in an orifice 3 that opens through the wall of the conical body 2 from below. The larger end of the body provides the outlet or mouth 4 of the cowl, and carries an outwardly flared peripheral flange 5, preferably a flange that is of greater extent or breadth at the top of the mouth and of gradually diminishing breadth towards the bottom. The body of the cowl includes at its smaller end a re-entrant portion 6 of frusto-conical form, and such reentrant portion provides the essential ejector tube of the cowl structure.

25 In keeping with usual practice the cowl is mounted for rotation upon a stationary base 7, the upper portion 7a of the base extending upward into the inlet 3 of the cowl. The base 7 affords communication between the cowl and the ventilating duct or passage 8 from which air is to be exhausted. The means for rotatably supporting the cowl are conventional, comprising a bearing block 9 carried by the base, and a vertical stem 10 secured to the cowl and bearing at its lower end upon the block 9. Braces 11 in the cowl laterally reinforce the stem, and a spider 12 in the portion 7a of the base provides a lateral bearing for the stem. As thus mounted, the cowl is freely rotatable on the vertical axis of the stem 10.

30 The cowl is equipped with a vane 13, whereby under the influence of the wind the cowl is maintained in such position that its mouth faces in downwind direction, with the ejector tube 6 directed into the wind.

35 The broken lines 20 indicate in outline the cone to whose contour the cowl body 2 is formed, and

it is important to note that the cowl body is so mounted on the base 7 that the axis 21 of the cone extends at an angle of less than 30° to the horizontal plane 22 (the angle being $8\frac{1}{2}$ ° in this case), with the larger end of the cowl directed upward. While the smaller or truncated end of the conical body lies in a plane approximately normal to the axis 21 of the cowl, the larger or basal end of the cone lies at an angle of less than 30°, here about 15°, to the normal base 23 of the cone, wherefore the cowl body at its top is substantially longer than at its bottom. These features of structural organization are of notable value, in that they minimize the effect of "throat constriction," which term is the name applied to the well-known tendency for the cowl to throttle the stream of air flowing through a ninety degree turn (from vertical to horizontal direction) within it.

It will be perceived that the entire cowl body may be formed of four pieces of sheet metal, one for the conical body 2 of the cowl, one for the conical ejector tube 6, one for the flange 5, and one for the vane 13. The arrangement of the ejector tube is particularly to be noted. The conical body of the tube is arranged with its taper opposite to the taper of the conical body 2 of the cowl, and the tube is united at its larger end to the smaller end of the cowl body, a simple rolled or crimped joint 16 being effective for the purpose.

In Figure II a cowl of the invention is provided with a cylindrical portion 30, which comprises a skirt around the inlet (3, Figure I) that opens through the wall of the cowl, and overlies the upper edge of the base portion 1a. By virtue of the skirt 30, the portion 1a of the base need not extend upward into the cowl body, as it does in the structure of Figure I. In further refinement an outwardly flared flange 60 is provided on the smaller end of the cowl body. This flange augments the efficiency of the ejector tube.

In each of the structures of Figures I and II, a counterweight 14 may be used to balance the cowl with respect to the vertical axis on which it rotates.

The cowl may be constructed in various sizes, depending upon the diameter of the ventilating duct or passage 8 with which the cowl is organized, and without limiting the invention to the specific values given the dimensions of the cowl for a duct 8 of 16" in diameter are:

1. Length of cowl on top=30".
2. Length of cowl on bottom=21".
3. Length of the axis of cone 20 to whose contour the cowl is shaped=41".
4. Diameter of the base 23 of the cone 20=33".
5. Diameter of the truncated end of the cone 20=10".
6. Angle between base 23 of the cone and the mouth 4 of the cowl=15°.
7. Length of the reentrant or ejector tube portion 6 of the cowl=10".
8. Diameter of the inner end of tube portion 6=4".
9. Diameter of the inlet 3 in the bottom of the cowl=17".
10. Breadth of the flange 5=5" at the top of the mouth of the cowl, and 1" at the bottom.
11. Angle between the outer or upper surface of the flange 5 and the outer surface of the cowl body=155°.
12. Diameter of the portion 1a of the base=16".
13. Breadth of the base 7 at the bottom=26".

14. Height of the base 24".

15. Angle between axis 21 of the cowl and the horizontal plane passing through apex of cone 20= $8\frac{1}{2}$ °.

16. Vane 13 is shaped to the proportions shown, to afford sufficient wind area and to be of pleasing appearance.

In the structure of Figure II the above dimensions will apply. Additionally, it may be noted that the skirt portion 30 is 17" in diameter, and at the front of the ventilator is of 3" in vertical extent, this affording sufficient data for the pattern maker. The flange 60 is 5" in breadth and extends at an angle of 105° to the surface of the cowl body.

The sheet metal used in the construction of the ventilator is 24 gage American Standard, and it will be understood that, in constructing cowls which are larger or smaller than the one described, sheet metal of greater or less thickness will be used. Due to the conical form of the cowl body the sheet metal of which the cowl body is constructed may be corrugated, thus obtaining greater rigidity of structure.

Within the scope of the definitions presented in the appended claims, various modifications and refinements are held in contemplation.

I claim as my invention:

1. In a ventilator including a cowl having an inlet for communication with a ventilating passage, an outlet, and means for supporting the cowl for rotation on a vertical axis; said cowl comprising a tubular body of truncated conical form arranged with the cone axis inclined at an angle of approximately $8\frac{1}{2}$ degrees to a horizontal plane and with the larger end of such conical body directed upward to form the outlet of the cowl, an outwardly flaring peripheral flange on the larger end of said conical body, the plane of said larger end of the so-arranged conical body being inclined at an angle of approximately 15 degrees to a plane normal to the axis of the conical body, whereby the outlet of said cowl is inclined downward from the top of the cowl body and inward towards said vertical axis, said inlet of the cowl opening from below through the side wall of said conical body, and a reentrant tubular portion extending inward from the smaller end of said truncated conical body to form an ejector tube.

2. In a ventilator including a cowl having an inlet for communication with a ventilating passage, an outlet, and means for supporting the cowl for rotation on a vertical axis; said cowl comprising a tubular body of truncated conical form having an outwardly flaring peripheral flange on each of its ends, said conical body being arranged with its axis inclined at an angle of less than 30 degrees to a horizontal plane and with its larger flanged end directed upward and forming the outlet of the cowl, the plane of said larger end being inclined downward and inward at an acute angle, said inlet of the cowl comprising a vertical tube that opens upwardly through the side wall of said conical body, the bottom surface of the so-arranged conical body being inclined downwardly from its smaller end towards its larger end, with the lower edge of said mouth lying at a point located below the upper edge of said vertical tube, and a tubular portion extending inward from the smaller flanged end of said conical body to form an ejector tube.

JAMES M. GUTHRIE.
